Primary Examiner — John Windmuller(74) *Attorney, Agent, or Firm* — McAndrews, Held & Malloy, Ltd.(57) **CLAIM**

The ornamental design for a retention clip, as shown and described.

DESCRIPTION

FIG. 1 is a perspective view of a retention clip;

FIG. 2 is left side view thereof;

FIG. 3 is a back view thereof;

FIG. 4 is a top view thereof;

FIG. 5 is a right side view thereof;

FIG. 6 is a front view thereof; and,

FIG. 7 is a bottom view thereof.

The broken lines in the drawings are included for the purpose of illustrating environmental subject matter and form no part of the claimed design.
